Attiss.

UNITED STATES PATENT OFFICE.

MORRIS COHEN, OF CHICAGO, ILLINOIS.

MALLET.

1,419,615.

Specification of Letters Patent. Patented June 13, 1922.

Application filed September 23, 1921. Serial No. 502,820.

To all whom it may concern:

Be it known that I, MORRIS COHEN, a citizen of the United States, residing at Chicago, in the county of Cook and State of Illinois, have invented a new and useful Improvement in Mallets, of which the following is a specification.

My invention relates more particularly, though not exclusively, to mallets for use 10 by glove cutters.

In the use of mallets, particularly in the manufacture of gloves, the principal wear on the mallet occurs adjacent the forward edge of the striking surface thereof, with the 15 result that this portion of the mallet becomes worn and impaired for use while the remainder of the head remains substantially unworn. In this connection it is one of my objects to provide a mallet the head of which 20 is reversible, adapting the head to be turned end for end and thus when one end portion of the head becomes worn the other, unimpaired, end portion thereof may be positioned at the forward end of the mallet, 25 thereby effecting a very substantial saving. A further object is to so house the means on the body portion which interlocks with means on the head to prevent the head from rotating on the body of the mallet, so as to 30 avoid sharp edges from coming in contact with the material on which the mallet is used, whereby to obviate all danger of injury to such material. Other objects are to provide a novel, simple and economical construction of mallet and to provide for the 35 substitution of a new head for a worn one when desired.

Referring to the accompanying drawing:

Figure 1 is a view in side elevation of a 40 mallet constructed in accordance with my invention. Figure 2 is a longitudinal sectional elevation of the mallet with a certain portion thereof shown in elevation and also partly sectional. Figure 3 is an end view of 45 the head portion of the mallet showing it as removed from the body thereof. Figure 4 is a view in side elevation of a portion of the rod forming a part of the body of the mallet. Figure 5 is an end view of the structure shown in Fig. 4, viewing it from the 50 left hand side of this figure; and Figure 6 is a face view of a lock washer employed.

The mallet shown is formed of a body portion 7 and a head portion 8, the body portion 7 comprising a rod member 9, preferably of metal, presenting a substantially

cylindrical portion 10 at one end, its extremity being threaded as represented at 11, a reduced, preferably tapered, portion 12 at its other end and concentric with the portion 10 and intermediate these portions, a hexagonal collar 13. The portion 12 is shown surrounded by a series of disks 14 preferably of leather which are disposed in flatwise relation to each other and are so shaped as to 65 present a handle 15 of a form adapting it to be conveniently and securely gripped by the workman, the extremity of the portion 12 being shouldered as represented at 16, against the adjacent one of the disks 14 and 70 together with the collar 13 maintaining these disks in tight condition upon the rod portion 12.

The rod 9 is provided, between the collar 13 and the threaded portion 11, with a projection which extends radially of the axis of the rod, for a purpose hereinafter described, this projection being shown as in the form of a pin 17 projecting radially from the portion 10 of the rod. 80

The head 8 of the mallet is formed of a sleeve-like member 18 adapted to be slipped over the portion 10 of the rod to the position shown in Fig. 2, one end of this sleeve being externally threaded as represented at 19 and 85 its opposite end provided with an annular flange 20, the end face of this flanged portion of the sleeve containing a recess 21. The striking surface of the head is preferably formed of a plurality of disks 22, of any 90 suitable material, as for example rawhide, which fit flatwise together and surround the sleeve 18, these disks being securely held in position relative to the sleeve by means of a ring 23 screwing upon the threaded portion 95 19 of the sleeve, whereby the disks are firmly clamped between the flange 20 and the ring 23, the ring 23 being provided in its end face with a recess 24. The head is securely, releasably, held on the rod 9 by means of a 100 nut 25 screwing upon the threaded portion 11 of the rod 9, the head being clamped between the flange 13 and the nut 25. A washer 26 is preferably confined between the nut 25 and the head 8, this washer being 105 27 which enters a longitudinal groove 28 in the rod portion 10.

The projection 17 which interlocks with the head at the recess 21 or 24, depending 110 on whether the flanged end of the head is adjacent the flange 13, or the ring portion

23 is adjacent this flange, serves to prevent rotation of the head on the body of the mallet.

It will be readily understood from the foregoing that the head 8 is rendered readily reversible end for end for the purpose hereinbefore stated, and substitution of a new head for one which has become worn out, may be readily effected upon removing the 10 nut 25.

While I have illustrated and described a particular construction involving my invention, I do not wish to be understood as intending to limit it thereto as the same may 15 be variously modified and altered without departing from the spirit of my invention.

What I claim as new and desire to secure by Letters Patent, is:

1. A mallet formed of a body portion affording a handle, a head carried by said handle and reversible end for end thereon, said head being formed of a sleeve whose bore receives said body portion and presenting flanges at its ends, and a body of striking

material surrounding said sleeve and confined between said flanges, and a radial projection from said body portion, said flanges containing recesses extending radially from the bore of said sleeve into which said projection extends in the alternative positions 30 of said head.

2. A mallet formed of a body portion presenting a flange between its ends, a head surrounding the outer end of said body portion and reversible end for end thereon and comprising a sleeve whose bore receives said body portion having flanges at its ends one of said flanges being removable, and a body of striking material surrounding said sleeve and confined between said flanges on the latter, a pin projecting radially from said body portion, said flanges containing recesses extending radially from the bore of said sleeve into which said projection extends in the alternative positions of said head, and a nut 45 screwing on the outer end of said body portion and against said head.

MORRIS COHEN.
